ELECTRODE STRUCTURE AND METHOD OF
MANUFACTUREWalter M. Trumbull, Newark, and Erice W. Kin-
yon, Bloomfield, N. J., assignors to Radio Cor-
poration of America, a corporation of Delaware

Application November 25, 1942, Serial No. 466,866

7 Claims. (Cl. 250—162)

1

Our invention relates to electron discharge devices and particularly to improved electrode structures for use in such tubes.

Many electron discharge tubes, and particularly those of the cathode ray type, require an electron beam forming electrode structure which is rigid and in which the relative positioning of the electrodes is maintained during life of the tube. Furthermore, the spacing requirements between electrodes of such tubes are very critical so that relative movement of one electrode with respect to another, such as the cathode with respect to the grid, is detrimental to tube operation. Thus indirectly heated cathodes in such tubes must be located with respect to an apertured control electrode very accurately and must likewise retain this positioning throughout tube life notwithstanding variations in operating temperature of the cathode. Such requirements for accurate spacing and rigidity have necessitated in the past a relatively costly electrode assembly requiring experienced labor and complicated mounting jigs for the assembly operation.

Among the objects of our invention are to provide a more rugged electrode structure for tubes of the type described, to provide an electrode assembly having a minimum of parts and wherein the relative positioning of the parts is maintained during use, to provide a structure which may be made without reference to close dimensional tolerances, is inexpensive and well adapted to accurate and rapid assembly in quantity production, to provide a structure wherein the distance between the various parts is determined without reference to the size of the parts and is maintained irrespective of mechanical shock and temperature changes during use, and to provide a method of assembly which is adapted to high production at low cost and which may be followed by inexperienced assembly personnel. These and other objects, features and advantages of our invention will become apparent to those skilled in the art when considered in view of the following description and the accompanying drawing wherein:

Figure 1 is a plan view of a cathode ray tube incorporating our improved electrode structure;

Figure 2 is an expanded view of certain of the electrode structure shown in Figure 1, and

Figure 3 is an electrode assembly fixture suitable for practicing our method of electrode assembly.

Referring to Figure 1, we have shown a cathode ray tube having an envelope 1 closed at one end with a stem member 3 supporting, preferably in

2

direct contact therewith, an electron gun generally designated as 5 to develop and direct an electron beam toward the opposite end of the envelope 1 such as upon a luminescent screen 7. In accordance with our invention, we provide a unitary electrode assembly which may be assembled prior to attachment thereof to the stem or other support member in the tube, the spacing of the various parts being predetermined and fixed prior to its attachment but without reference to individual part sizes or tolerances. Where our electrode assembly is to be affixed to the stem of the tube through which lead wires enter the envelope, we prefer to use a stem of the so-called meridian or button type wherein the lead wires are arranged in an annular disposition.

Referring to Figure 2, we have shown the stem member 3 as comprising an apertured disc 9 of glass having a centrally disposed closure or exhaust tube 11. The disc 9 supports and is sealed to a number of lead wires 13 extending through the disc and preferably arranged annularly about and closely within the periphery thereof. Preferably, the disc 9 is provided with integral extensions or beads 15 surrounding each of the lead wires. In accordance with our invention we provide a planar member extending transversely of the tube on which the electrodes comprising the electron gun are rigidly affixed. Referring again to Figure 2, our electrode structure comprising the heater, cathode and grid is supported by a planar insulating member 17 of sufficient thickness to be substantially rigid and which is slotted so that the electrodes may be affixed to one side thereof and so that the resulting assembly may be closely adjacent the stem 3 preferably in contact with and supported by the beads 15 formed integrally with the stem disc 9. The insulating member 17 is provided with apertures having a plurality of open-ended eyelets spatially aligned with the lead wires 13 so that the disc member following assembly, as hereinafter described, may be slipped over the leads and brought to rest against the beads 15. More particularly, we prefer to provide three or four apertures provided with crimped eyelets 19 having flanged portions extending above the surface of the disc member 17 so that, following assembly, they may be affixed to the respective lead wires such as by welding or crimping. The disc member 17 directly supports a heater 23 through contact terminals 25 which may be narrow bands of metal extending through the disc member 17 and crimped

thereto for the purpose of support and current conduction to the heater.

In the expanded view of Figure 2 we have shown the cathode and its supporting structure directly above the heater 23 and aligned therewith. Preferably this structure in accordance with our invention comprises an outer cathode support cylinder 27 supporting an inner cylinder having a closed end provided with electron emitting material which serves as the cathode 29, the two cylinders being maintained in longitudinal fixed relation by a pair of cathode support straps 31. These support straps 31 are preferably affixed at their cathode ends on opposite sides of the cathode axis with the opposite ends affixed to the cylinder 27 in a manner described below. The points of support on the cylinder 27 are preferably out of line with the points of support on the cathode 29 so that upon heating the cathode, axial longitudinal motion resulting from expansion is not imparted to the cathode. For this reason we prefer to affix the cathode support straps 31 to the cathode closely adjacent its upper end so that any expansion over the length of the cathode is in a downward direction. We prefer to provide a plurality of integral extensions on the cylinder 27 such as the three lugs 33 and likewise provide slots 35 in the planar insulating member 17 into which the lugs 33 may be fitted so that the end of the cylinder 27 abuts and is affixed to the member 17 with the cathode 29 surrounding the heater 23.

The grid of our electrode structure preferably comprises a cylindrical member 37 with its one end abutting the insulating member 17 and affixed thereto in permanent relation to the cathode support cylinder and cathode. Other electrodes may be supported by the grid cylinder through ceramic tubes 39 held to the grid cylinder by integral flanges 41. Greater rigidity may be provided for the remaining electrodes by metal conductors 42 passing through the ceramic tubes 39 and affixed to eyelets 43 in the insulating member 17. The grid cylinder 37 is preferably closed at its upper end with an apertured disc 45 and provided around its lower edge with lugs 47 so that the cylinder may be rigidly attached to the insulating member 17 such as by passing the lugs 47 through the apertures or slots 49 in the insulating member 17.

In assembling our electrode structure the contact terminals 25 are first affixed to the insulating member 17 and the legs of the heater 23 welded or pinched to these conductors so that the heater is supported in an upright position with its axis normal to the member 17. A mounting fixture such as shown in Figure 3 is then utilized to provide the proper spacing between the upper end of the cathode 29 and the apertured grid disc 45 irrespective of large variations in part dimensions or tolerances. Referring to Figure 3, the fixture shown comprises a mandrel 50 of relatively large diameter provided with a tip or arbor portion 52 of reduced diameter substantially equivalent to the inside diameter of the cathode 29. The mandrel 50 is surrounded by two collars 54 and 56, the collar 54 being free to rotate about the mandrel 50. Furthermore, one surface of the collar 54 is utilized as a reference surface and is provided with apertures or slots corresponding in position about the axis of the mandrel and arbor to the slots 35 and 49 in the insulating member 17 which correspond to the positioning of the lugs 33 and 47

on the cathode support cylinder 27 and grid cylinder 37 respectively. The second collar 56 is provided with a set screw 58 so that it may be locked or secured to the mandrel 50 at any position along its axis. The collar 54 is provided with a cylindrical sleeve 60 having an external diameter approximately equal to the internal diameter of the cathode support cylinder 27 minus the thickness of the two cathode support straps 31, and an internal diameter larger than the diameters of the cathode 29 and the arbor 52. In addition, the sleeve 60 is provided with a pair of oppositely disposed slots or recesses 62 corresponding in position to the desired location of the cathode support straps 31.

Prior to assembly of the electrode structure utilizing the fixture of Figure 3, we affix the cathode support straps 31 at one end to the cathode 29 and slip the cathode over the arbor 52 so that the straps 31 lie in the recesses 62. The cathode support cylinder is then seated on the collar 54 with the lugs 33 in the corresponding slots. A spacer 64 is then prepared having a thickness corresponding exactly to the desired cathode-apertured grid disc spacing which is placed over the end of the cathode. The grid cylinder 37 carrying the grid apertured disc 45, preferably welded thereto, is then slipped over the sleeve 60 and the lugs 47 slipped into the corresponding slots in the collar 54. The set screw 58 in the collar 56 is then loosened to allow the mandrel 50 and arbor 52 to be pushed forward holding the spacer 64 in firm contact between the cathode 29 and the apertured grid disc 45, following which the set screw 58 is again secured to the mandrel 50. This operation effectively spaces the cathode with respect to the apertured grid disc while at the same time seating the ends of the cathode support cylinder 27 and grid cylinder 37 in flush relation on the collar 54. Following this assembly operation, the ends of the cathode support straps 31 opposite the cathode are affixed to the cathode cylinder 27. This operation may be performed by providing the sleeve 60 as one electrode in a welding circuit and welding the straps 31 to the cathode support cylinder 27. The parts thus accurately spaced may be removed from the mounting fixture, the spacer 64 discarded for future use and the parts assembled on the insulating member 17 previously provided with the heater 23. Since the surface of the collar 54 conforms to the surface of the member 17, the parts are accurately spaced on the member 17 by slipping the lugs 33 and 47 through the corresponding slots 35 and 49 in the member 17 so that the lower edges of the cylinders 27 and 37 are in the same spatial relationship as when on the collar 54 such as flush and in contact with the member 17, whereupon the lugs may be bent over or twisted to permanently secure the cylinders to the insulating member followed by affixing the conductors 42 to the eyelets 43 and assembly of the remaining electron gun parts thereto.

The cathode and grid structure assembled with the insulating member 17 is then fastened to the stem 3 by slipping the eyelets 19, previously affixed to the member 17, over the correspondingly positioned lead wires 13, whereupon the collar portion 21 of the eyelets may be welded to the corresponding lead wires. Preferably a series of apertures corresponding in number and position to the lead wires are provided in the 75 insulating member 17 so that when this member

carrying the cathode grid assembly is slipped over the lead wires, the insulating member 17 abuts and is held securely against the beads 15 of the stem.

In this final assembly operation it will be noted that the lower edges of the cathode support cylinder and grid cylinder occupy an identical position as previously occupied against the collar 54 of the Figure 3 fixture. Consequently, the relative spacing between the cathode and apertured grid cylinder will be the same and correspond exactly to the thickness of the discarded spacer 64. It will be further appreciated that the straps 31 being affixed to the cathode adjacent the spaced end will provide a minimum portion of the cathode free to expand in an axial direction when heated. Any expansion of the straps 31 will tend to rotate the cathode about its axis, but such expansion will not cause relative displacement of the cathode along its axis. Consequently, the cathode remains in a fixed axial position notwithstanding variations in operating temperature, and the spacing between the cathode and apertured grid disc will be constant during use.

From the foregoing description it will be appreciated that our improved construction provides a rigid structure including the ceramic tubes 39 to which the other electrodes of the mount structure may be assembled. For example, referring to Figure 1, which shows the mount structure assembled in the envelope 1, the first anode 70 is provided with flanges affixed directly to the ceramic tubular rods 39. The second anode discs 72 and 74 are similarly affixed to the tubular rods 41 which likewise support the conventional deflection plates 76 and 78. Furthermore, it will be appreciated that the resulting mount structure is rigid and will withstand the usual shocks and abuse during use of the tube.

We claim:

1. An electrode assembly for an electron discharge device comprising a planar insulating member, a cylinder having one end abutting one side of said member and having lugs extending therethrough and clinched against the opposite side thereof, a cathode, straps having one of their ends secured to said cathode near the end thereof opposite that abutting said member and the other one of their ends secured to said cylinder, a second cylinder surrounding said first cylinder and having one end abutting the said one side of said member and having lugs extending therethrough and clinched against the opposite side thereof and an apertured disc in said second cylinder with the aperture aligned with said cathode.

2. An electrode assembly for an electron discharge device comprising a multi-apertured planar member, a cylinder having one end abutting said member and having tabs thereon extending through the apertures of said member, a tubular cathode having one end closed, arms secured to said closed end and to the said cylinder to support the cathode coaxially within said cylinder, a second cylinder of larger diameter than said first cylinder having one end abutting said member and having tabs thereon extending through other apertures of said member and surrounding said first cylinder, an apertured element supported in the end of said second cylinder opposite said member and a heater within said cathode having its end conductors extending out the open end of the cathode and through open-

ings in said disc and back through other openings in said disc, whereby it is supported directly by said member.

3. An electrode assembly comprising an insulating disc having openings extending therethrough, a hollow cylinder having an end edge normal to its axis with lugs extending through said openings and deformed to hold said edge against a side surface of said disc, a second hollow cylinder smaller than the first cylinder having an open end and a closed end, electron emitting material on the outside surface of said closed end, and arms having one of their ends secured to the smaller cylinder adjacent its closed end and

15 the other of their ends secured to the larger cylinder adjacent the end remote from said disc and arranged to position the smaller cylinder coaxially within the larger cylinder.

4. An electrode assembly comprising an insulating disc having openings extending therethrough, a hollow cylinder having an end edge normal to its axis with lugs extending through said openings and deformed to hold said edge against a side surface of said disc, a second hollow cylinder

25 smaller than and within the first cylinder having an open end and a closed end, electron emitting material on the outside surface of said closed end, and arms having one of their ends secured to the smaller cylinder adjacent its closed end and the other of their ends secured to the inner side of said larger cylinder adjacent the end remote from said disc with the open end of the smaller cylinder spaced from said disc.

5. An electrode assembly comprising an insulating disc having openings extending therethrough, a hollow cylinder having an end edge normal to its axis with lugs extending through said openings and deformed to hold said edge against a side surface of said disc, a second hollow cylinder smaller than and within the first cylinder having an open end and a closed end, electron emitting material on the outside surface of said closed end, arms having one of their ends secured to the smaller cylinder adjacent its closed end and the other of their ends secured to the inner side of said larger cylinder adjacent the end remote from said disc with the open end of the smaller cylinder spaced from said disc, and a heater having its end conductors extending out the open end of the cathode and through openings in said disc and back through other openings in said disc, whereby it is supported on said disc and extending into the smaller cylinder.

6. An electrode assembly comprising an insulating disc having openings extending therethrough, a first and a second hollow cylinder, each having an end edge normal to its axis with lugs extending through said openings and deformed to hold each of said edges against a side surface of said disc, with the second cylinder inside the first cylinder and spaced therefrom, a third hollow cylinder having an open end and a closed end, electron emitting material on the outside surface of said closed end, arms having one of their ends secured to the third cylinder adjacent its closed end and the other of their ends secured to the second cylinder adjacent the end remote from said disc, and a member secured to the unattached end of said first cylinder having an aperture substantially in line with the axis of the third cylinder and spaced from the closed end thereof.

7. An electrode assembly comprising an insulating disc having openings extending therethrough, a first and a second hollow cylinder,

each having an end edge normal to its axis with lugs extending through said openings and deformed to hold each of said edges against a side surface of said disc with the second cylinder inside the first cylinder and spaced therefrom, a third hollow cylinder having an open end and a closed end, electron emitting material on the outside surface of said closed end, arms having one of their ends secured tangentially to the outside surface of the third cylinder adjacent its 10

closed end and the other of their ends secured tangentially to the inside surface of the second cylinder adjacent the end remote from said disc, and a cap secured to the unattached end of said first cylinder having an aperture of less area than the electron emitting material on said closed end and aligned with the axis of the third cylinder.
